(57) CLAIM

The ornamental design for a skincare device, as shown and described.

DESCRIPTION

FIG. 1 is a perspective view of a skincare device, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the drawings depict portions of the skincare device that form no part of the claimed design. The shade lines in the Figures show contour and do not claim surface ornamentation or treatment.
